HAIR WAVING DEVICE

Wilbur S. Lewis, Cleveland, Ohio, assignor to The Murle Co., Cleveland, Ohio, a corporation of Ohio

Application October 31, 1935, Serial No. 47,647

2 Claims. (Cl. 132—36)

This invention relates to a device for forming curls in strands of hair by what is known as permanent waving. The present invention is an improvement on the hair waving device illustrated, described and claimed in United States Patent No. 1,974,625 issued September 25, 1934 jointly to John C. Murray and myself.

An object of the present invention is to provide a hair waving device which may be more readily manufactured and assembled, and which is composed of fewer parts than the device shown in said Patent No. 1,974,625.

Another object of the invention is to provide in a hair waving device of this character integral means forming the hair clamping means and the means for insulating the device from the scalp of the person being treated.

Further and additional objects and advantages not hereinbefore referred to will appear herein-after during a detailed description of the device which is illustrated in the accompanying drawing wherein:

Fig. 1 is a perspective view of the device on an enlarged scale.

Fig. 2 is a sectional view thereof taken substantially on line 2—2 of Fig. 1 looking in the direction of the arrows.

Fig. 3 is a detail perspective view of the integral clamping and insulating pad, and

Fig. 4 is a detail perspective view of the metal connecting clip used with said insulating and clamping pad.

In view of the fact that the construction of the device shown herein is identical with that shown in said Patent No. 1,974,625, with the exception of the integral insulating and clamping member, it is believed that only a brief description of the corresponding details of structure need be set forth herein.

The device constitutes what is known as a heater and is constructed to be used with steam as the heating agent, although it should be understood that the device might also employ electrical or chemical heating means. The heater constitutes a chamber, which chamber is formed of two half sections 10 and 11, preferably made of suitable sheet metal, each section being substantially U-shaped in cross-section. The sections are pivotally connected together adjacent one of their ends, wherefore they may be swung to open position to allow the strands of hair to be clamped upon a rod 12 which is rotatably carried by the heater and upon which the hair is wound. The hair sections 10 and 11 are closed upon the rod 12 when heat is to be applied to hair wound

upon the rod and said sections are clamped and locked in closed position by means of spaced links 13 pivotally connected to the section 11 at the end opposite to the pivotal connection between the sections and adapted to receive therebetween a tongue 14 carried by the section 10. A locking cam or eccentric 15 is pivotally mounted between the links 13 at the free ends thereof, and when said cam or eccentric is turned into engagement with the tongue 14 by the handle 16 the two half sections of the heater or chamber are fully closed and locked in that relationship. The section 11 intermediate the ends of the heater and adjacent the bottom edge is provided with an opening in which is mounted a swiveled fitting 17 for receiving and connecting to the heater a steam inlet conduit 18, as clearly shown in Figs. 1 and 2. The tongue 14 carried by the section 10 is the extended end of a plate 19 secured to the outer side of the section 10. A similar plate 20 is secured to the outer side of the section 11 and has an extended end to which the links 13 are pivotally connected. The opposite ends of the plates 19 and 20 are similarly extended beyond the sections and have pivotally connected thereto spaced links, not shown herein, which form the hinged connection between the half sections and to one of which the rod 12 is rotatably connected. Channels 21 are secured to the outer sides of the plates 19 and 20 which channels have the ends of their arms turned inwardly of the channel, as shown at 22, for a purpose later to be explained.

The substantially Z-shaped metal members 23 are secured to the sections 10 and 11, it being noted that the long arms of the members 23 extend within the sections 10 and 11 and are secured to the side walls thereof. The members 23 embrace the plates 19 and 20, while their outer portions constitute channels 23a, the bases of which bear against the adjacent sides of the separate channels 21 which are secured to plates 19 and 20 and to the members 23 by suitable rivets or other securing means. The description of the heater thus far set forth is identical with the construction of the heater shown in the said Patent No. 1,974,625.

In accordance with the present invention the inner arms of the channels 23a of the Z-shaped members 23 are provided with a plurality of openings 24, in the present instance there being three of these openings, and said openings constitute part of the securing means for the combined hair clamping and insulating member. This member, indicated in its entirety by the numeral 25, is an integral rubber pad having on one side and at one

edge thereof an upstanding rib 26 provided on each of its sides with undercut, longitudinally extending grooves 27. Spaced from the rib 26 and extending parallel thereto intermediate the longitudinal edges of the pad is a second upstanding rib 28 which has secured thereto a metal channel 29, the ends of the arms of which are bent inwardly, as indicated at 29a, so as to clamp the channel in position upon the rib 28. The channel 29 is provided with a plurality of spaced outstanding knobs or projections 30, there being three of these projections in the present illustration, inasmuch as there are three of the openings 24 in the channel 23a.

15 In assembling the combined clamping and insulating members upon the heater the inturned ends 22 of the channels 21 are slipped into the undercut grooves 27 adjacent one end of the rib 26, and then the members are slid longitudinally 20 into position on the heater, which action brings the ribs 26 into the channels 21. When the members have been thus positioned with the ribs 26 in the channels 21 they are then bent around to position the channels 29 and the ribs 28 within the 25 channels 23a and such positioning of the channels 29 causes the knobs or projections 30 carried thereby to snap into the openings 24 in the channels 23a, wherefore the channels 29 with their cooperating ribs 28 are securely locked in position in the channels 23a. It will be seen due to the manner in which the rib 26 is secured in the channels 21 and the ribs 28 and associated channels 29 in the channels 23a, that the combined 30 clamping and insulating members are securely 35 attached to the heater and in a manner allowing for great ease of assembly.

It will be understood that the portions of the members which lie adjacent to the ribs 28 when the members are mounted on the heater, constitute 40 the hair clamping portion of the members,

while those portions of the members lying outwardly of the channels 21 and 23a are the insulating portions thereof and are adapted to be located adjacent to the scalp of the person being treated when the heater is being used.

5 Although a preferred embodiment of the invention has been illustrated and described herein it should be understood that the invention is susceptible of various modifications and adaptations within the scope of the appended claims.

10

Having thus described my invention I claim:

1. In a hair waving device of the character described and including a heater formed of two pivotally connected sections each of which has connected to one of the sides thereof a pair of 15 channels with the channels of each pair disposed so as to face at right angles to each other, and combined insulating and hair clamping members secured to said device and comprising integral rubber pads each having on one side thereof a 20 pair of spaced parallel ribs, one of which extends into one of the channels of said pair and the other of which extends into the other of the channels of said pair, and means for locking said ribs in 25 said channels.

2. In a hair waving device of the character described and including a heater formed of two sections each of which is provided with means for supporting a hair clamping member and means for supporting an insulating member, in combination with combined insulating and hair clamping members secured to said device and each comprising integral rubber pads having a clamping portion and an insulating portion, said portions and both of said means having cooperating elements 30 providing an interlock therebetween acting to maintain the combined insulating and hair clamping members in position.
